UNITED STATES PATENT OFFICE.

GEORGE W. MITCHELL, OF NEW YORK, N. Y., ASSIGNOR TO LEVI M. ROSENTHAL, OF MOUNT VERNON, NEW YORK.

BOTTLE-CAP.

1,139,792.

Specification of Letters Patent.

Patented May 18, 1915.

Application filed July 24, 1912, Serial No. 711,293. Renewed September 20, 1913. Serial No. 790,854.

To all whom it may concern:

Be it known that I, GEORGE W. MITCHELL, a citizen of the Dominion of Canada, resident of New York, in the county of New York and State of New York, have made a certain new and useful Invention in Bottle-Caps; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a central vertical section of the invention in its normal shape, applied to the bottle. Fig. 2 is a similar view with the cap compressed to seal the bottle. Fig. 3 is a plan view of the cap. Fig. 4 is a side view of the same. Fig. 5 is a central vertical section of the cap, the disk being removed.

The invention relates to improvements in means for closing bottles in an airtight manner, and it consists in the novel construction and combinations of parts, as hereinafter set forth.

The ordinary pliable or sheet metal bottle caps of tin fail to completely close the bottles, because in their structure sufficient allowance is not made for slight nicks or irregularities of shape of the marginal portion of the bottle neck, these being usually on the upper or outer portions of the margin, which are more exposed to casual injury than the inner surface of the marginal entrance. By the present device it is designed, to a great extent, to obviate this difficulty.

In the annexed drawing, illustrating the invention, the numeral 2 indicates the upper portion of the neck of an ordinary bottle, having the usual exterior marginal bead terminating in a circumferential shoulder 3, the margin of the mouth of the bottle being rounded inward and downward from its top surface, as indicated at 4.

A circular closure cap 5, made of thin metal, is designed to be pressed in normal shape, in which it is provided with a downward and outward turned flange 6, which may be marginally crimped in the usual manner. The upper part of the flange is smooth, joining the top 7 of the cap in a rounded bend 8, and the top is provided with a hollow boss or circular rise 9 in its central portion, the top of this raised central

part being connected to an annular slightly convex portion 10, around it, by its straight inclined wall 12 so that it has the form of a conical frustum. The top of the frustum-shaped rise may be plane or slightly convex, and the conical inclined wall 12 slopes straight downward and outward therefrom to the annular portion of the cap, being connected to said top and said annular portion respectively by convexed and concave rounded bends. On its interior or under surface the rise 9 appears reversed, or as an indentation or circular recess seat having a straight sloping or beveled circular side wall joining the annular portion 10 of the cap. In this cap is fitted a thick circular disk 14 of soft elastic material, such as rubber, which is designed to hold its place in the seat by its elasticity, its edge being automatically pressed against the inside of the downward turned flange. The diameter of the central rise of the cap is slightly less than that of the inner circumferential surface of the mouth of the bottle and its sloping wall is designed to have the strength of a cone-like structure wherein the inclined elements are straight.

The cap in normal shape is to be applied to the top of the bottle neck in the usual manner, the crimped flange being pressed inward under the bead of the neck and against its shoulder. At the same time it is designed that the annular portion 10 of the cap shall be brought against the surface of the end of the bottle neck and that the frustum-shaped rise 9, centering the disk 14, shall be forced bodily inward, carrying down with it, because of the inherent strength of its straight cone-shaped walls, the adjacent part of the annular portion 10 of said disk and giving it a downward slope the means for depressing the rise being well known in the art, to approximate the rounded surface of the inside of the mouth of the bottle and forcibly press against this rounded surface the underlying portion of the disk, which, being elastic, will form a tight joint between said downward slope and the surface of the bottle mouth, and provide an effective closure. In this operation the normal upstanding form of the central rise is preserved, because of the strength of its conical high-angle wall. At the same time the thickness of the rubber disk gives it sufficient body to act, in connection with the downward slope or bend of the annular portion of the cap,

as a plug, and thereby the appliance is made suitable to accommodate slight variations in the size or shape of the rounded inside surface of the mouth of the bottle.

5 I do not desire to be limited to the details of the embodiment disclosed, but may vary them within the scope of the claims, and may use the closure and cap upon all receptacles similar to bottles.

10 Having described the invention, what I claim and desire to secure by Letters Patent is:

1. A closure for bottles and like receptacles, comprising a sheet metal bottle cap 15 adapted for use with a packing, comprising a raised boss centrally of the cap, and having a rigid wall extending downwardly from the raised top of said boss, the inner end of the said boss having a diameter less than that 20 of the orifice of the bottle to which the cap is to be applied, an annulus extending circumferentially away from the lower end of the said rigid wall of the said boss, and bendable by the downward and inward movement of 25 the boss to an upward slope away from the said lower end of the said rigid wall of the said boss, the said rigid wall of the said boss during and after the downward movement thereof extending downwardly from the top 30 of said boss to said annulus, and gripping means at the periphery of the said annulus.

2. A closure for bottles and like receptacles, comprising an elastic member, means for holding the peripheral portion of said 35 member against the external walls of the orifice of the bottle, and means for maintaining the central portion of the said member tensed and extended, and depressed with respect to the peripheral portion thereof, 40 said central portion being within the orifice of the bottle.

3. A closure for bottles and like receptacles, comprising a stretchable disk, means for holding the peripheral portion of said 45 disk against the external walls of the orifice of the bottle, and means for maintaining the central portion of the disk tensed and extended, and depressed with respect to the peripheral portion thereof, said central portion 50 being within the orifice of the bottle, the part of said central depressed portion of the said disk adjacent the internal walls of the orifice of the said bottle being forced against said internal walls.

55 4. A closure for bottles and like receptacles, comprising an elastic member, a cap, the peripheral portion of said cap being adapted to hold the peripheral portion of

said elastic member against the external walls of the orifice of the bottle, the central portion of said cap being driven below the peripheral portion thereof, the said elastic member being extended and maintained in a tensed condition within the orifice of the bottle.

5. A closure for bottles and like receptacles, comprising an elastic disk, a cap, the peripheral portion of said cap holding the peripheral portion of the elastic disk against the external walls of the orifice of the bottle, 70 the central portion of said cap being driven below said peripheral portion thereof, the said elastic disk being extended and maintained in a tensed condition within the orifice of the bottle.

6. In combination, a sheet metal bottle cap and a bottle, said cap comprising an annular portion, and a hollow boss projecting upwardly from said annular portion and having an upstanding periphery joined to said 80 annular portion, soft material held by the said annular portion intermediate said cap and the said bottle, means for securing said annular portion to said bottle, a portion of said annular portion being spaced from and 85 out of contact with the interior periphery of said bottle, so that it can be bent against said interior periphery, said boss being of such rigidity and said annular portion being so bendable, that, when said boss is depressed, 90 it causes the said annular portion to be depressed and driven toward the interior periphery of said bottle, whereby said soft material is compressed against said bottle to form a closure, the width of said boss at 95 its junction with the said annular portion and the rigidity thereof being such that said periphery of said boss remains upstanding when the said soft material is compressed against the said bottle.

7. A closure for bottles and like receptacles, comprising an elastic disk, means for holding the peripheral portion of said disk against the external walls of the orifice of the bottle, and means for maintaining the 105 central portion of said disk tensed and extended, and depressed with respect to the peripheral portion thereof, said central portion being within the orifice of the bottle.

In testimony whereof I affix my signature, in presence of two witnesses.

GEORGE W. MITCHELL.
